HEAT INTERCHANGE APPARATUS

William Lane De Baufre, Lincoln, Nebr.

Application August 9, 1934, Serial No. 739,973

3 Claims. (CL 257—225)

This invention relates to improvements in the art of exchanging heat between fluids of different temperatures. It is particularly applicable to heat interchange between one fluid under high pressure and two or more fluids under low pressure, as is the case in the rectification of atmospheric air and other mixed gases.

One object of the invention is to eliminate the tendency of the high pressure fluid to force tube sheets from the tubes affixed therein, as has heretofore been the case with straight-tube interchangers used in air separation plants, and yet retain the feature of permitting relative expansion of shell and tubes without undue strain on either shell or tubes.

Another object of the invention is to provide means for conducting two or more low pressure fluids through straight tubes in heat exchange with a high pressure fluid surrounding the tubes.

Another object of the invention is to utilize a metal shell of maximum strength due to cold work to withstand the high pressure fluid, and yet secure gas tight joints where the shell is joined to the heads of the interchanger.

Another object of the invention is to reinforce the cold worked shell where the strength has been reduced by annealing in securing gas tight joints by soldering, brazing or welding.

The foregoing, together with such other advantages as may hereinafter appear or are incident to the invention, are realized by the construction illustrated in preferred form in the drawing.

The improvements herein described and claimed are intended for interchangers of air separation plants as described in U. S. Patent No. 1,951,185, issued March 13, 1934. They are particularly applicable to high pressure throttle expansion plants as shown in Fig. 2, although certain features are also useful in moderate pressure plants as shown in Fig. 1 of the above patent. In such air separation plants, compressed air is cooled in an interchanger by returning products of rectification, consisting of more or less pure oxygen and nitrogen. Where such interchangers are provided in pairs with piping and valves arranged as shown in the above-mentioned patent and the flow of fluids is quickly changed from one interchanger to the other, the temperatures of the metal tubes will quickly change while the temperatures of the metal shell will change more slowly from the old to the new conditions. There will thus be relative expansion or contraction of tubes to shell which would tend to injure the tubes or the shell or the joints

between tubes or shell and tube sheets into which the tubes are affixed, unless provision is made to eliminate such strains. Interchangers have been built for moderate compressed air pressures with an expansion joint in the shell. In this construction, however, the full tendency of the internal fluid pressure to force the heads apart, is exerted upon the means by which the tubes are affixed in the tube sheets. While this construction is safe for moderate pressures, it is unsafe for very high pressures.

In building such interchangers, there is also a problem involved in constructing the heads for returning two or more fluids through the tubes so that no leakage of one fluid will occur to the external air or into a compartment containing another fluid.

For moderate air pressures, the shells of such interchangers have been made of copper to avoid corrosion. For very high air pressures, however, the thickness of a copper shell would be excessive, resulting not only in high first cost but also in difficulties during construction and operation. A high tensile strength bronze would therefore be more desirable than copper. The strength of such bronzes, however, depends largely on cold working, such as would occur in drawing a tube for an interchanger shell. In assembling such interchangers, soldering, brazing or welding is necessary to secure gas tight joints of fused metal. The application of heat for this purpose would anneal the hardened tube, thereby reducing the strength of the cold worked bronze to that of annealed material. During operation, however, in air separation plants and in similar gas liquefaction processes, the temperatures in interchangers are low so that advantage could be taken of the high working stresses permissible in cold worked bronze.

In the interchanger described herein and shown on the drawing, an arrangement and construction have been adopted which enables full advantage to be taken of the high working stresses permissible in cold worked bronze, at the same time permitting fused metal joints to be obtained by soldering, brazing or welding. The method of making and arrangement of interchanger for utilizing a cold worked metal shell are claimed in a divisional application filed August 9, 1935, Serial No. 36,882. This construction also eliminates strains due to differences in cooling and heating shell and tubes and reduces stresses on tubes due to high air pressures. At the same time, two or more low pressure fluids may be returned through the tubes in heat inter-

change with a high pressure fluid surrounding the tubes.

The interchanger consists of a number of small straight tubes 1 within shell 2 and extending between tube sheet 3 at the upper end and tube sheet 4 at the lower end. Tube sheet 3 at the upper end is part of a casting or forging 5 which has a larger internal diameter than the external diameter of shell 2. The gap between shell 2 and head 5 is filled by sleeve 6 which extends beyond head 5 over shell 2.

For mechanical strength of the joint between shell 2 and sleeve 6, shell 2 is threaded externally and sleeve 6 is threaded internally so that sleeve 6 can be screwed onto shell 2 and the sleeve held in place by interlocking of the threads. Sleeve 6, however, extends beyond the external threads on shell 2 over the unthreaded portion of shell 2. The object of this construction is to fully reinforce the threaded portion of shell 2 and to extend this reinforcing a short distance beyond the threaded portion where the shell has not been weakened by cutting threads thereon. If the reinforcing sleeve were not carried beyond the threaded portion of the shell, the shell might fail by fatigue cracks starting from the roots of threads at and beyond the edge of the reinforcing sleeve due to concentration of stresses at the roots of these threads. But by extending sleeve 6 beyond the threaded portion of shell 2, such concentration of stress is avoided by the reinforcing action of sleeve 6. For similar reasons, sleeve 6 is threaded externally and screwed into head 5 which is threaded internally, and head 5 is extended beyond the threaded portion of sleeve 6.

The joints between shell 2 and sleeve 6 and between sleeve 6 and head 5 are made gas tight by soldering, brazing or welding, thus forming fused metal joints. But the heating of the cold drawn metal shell 2 in order to solder, braze or weld the joint between it and sleeve 6 results in annealing the end of shell 2 and thereby considerably reducing the strength from that corresponding to the cold drawn condition.

The length of sleeve 6, however, is made such that the annealed portion of shell 2 is reinforced by sleeve 6 which extends a sufficient distance from the end of shell 2 to cover all portions of shell 2 which have been sufficiently heated by soldering, brazing or welding to appreciably reduce the strength of the cold worked metal. Sleeve 6 should preferably have a close fit over shell 2, but in any event, sleeve 6 will effectively reinforce shell 2 as soon as shell 2 has expanded by creep, or plastic flow, of the metal where the strength has been reduced by annealing.

Sleeve 6 is extended a sufficient distance beyond head 5 to prevent annealing shell 2 beyond sleeve 6 by conduction of heat thereto when the joint between sleeve 6 and head 5 is made gas tight by soldering, brazing or welding.

The construction described above and shown on the drawing provides an annular space surrounding the tube bundle between the ends of shell 2 and sleeve 6 and the tube sheet 3 of head 5. This annular space has the advantages of the recess claimed in U. S. Patent No. 1,823,388 in reducing the danger of obstructing outlet pipe 7 by snow and ice in a gas liquefaction plant. The inside diameter of shell 2 is but slightly greater than the outside diameter of the bundle of tubes 1. In addition to the advantages previously described, the construction shown enables 75 this recess to be formed with a head 5 of simple

shape that may be easily machined and forged rather than cast, and thus have the high strength and non-porosity required for gases under high pressure.

Small diameter tubes 1 are soldered or brazed into tube sheet 3. Tubes 1 are preferably arranged in concentric circles so as to form a round tube bundle suitable for enclosing in a cylindrical shell 2. This arrangement of tubes 1 is also suitable for dividing the tubes into two or more groups for returning products of rectification in an air or other gas separation plant.

In order that returning oxygen may flow through a central group of tubes and returning nitrogen may flow through the remaining tubes, the upper head is arranged as shown on the drawing. A shell 8 with flange 9 is soldered or brazed into a circular groove 10 in tube sheet 3 so that shell 8 will embrace as many openings in tube sheet 3 to tubes 1 as may be desired for the returning oxygen. A second shell 11 is then fastened to tube sheet 3 by flange 12 and bolts 13, suitable packing material being placed between flange 12 and tube sheet 3 to secure a gas tight joint. Shell 11 also rests on flange 9 and has a hole through it equal in diameter to the inside diameter of shell 8. A cap 14 with flange 15 is fastened to flange 9 by bolts 16, thereby clamping shell 11 between flanges 9 and 15, suitable packing material being placed between flange 9 and shell 11 and between flange 15 and shell 11 to secure gas tight joints. The height of shell 11 is made such relative to the distance of flange 9 from tube sheet 3 that when shell 11 is bolted to tube sheet 3 by bolts 13, it will also be forced against flange 9.

Cap 14 has inlet pipe 17 for returning oxygen to the portion of tubes 1 embraced within shell 8. Shell 11 has inlet pipe 18 for returning nitrogen to the portion of tubes 1 embraced between shell 8 and shell 11.

The lower ends of tubes 1 are affixed in tube sheet 4 which is made an integral part of floating head 19 by screwing and soldering it therein or by any other suitable construction. Due to the high gas pressures involved, the outside diameter of floating head 19 must be considerably greater than the inside diameter and may even be greater than the outside diameter of shell 2. Outer head 20 therefore has an inside diameter greater than the outside diameter of shell 2. The gap between shell 2 and outer head 20 is filled by sleeve 21. The proportions of sleeve 21 relative to shell 2 and to outer head 20 are made as described for sleeve 6 and head 5, and for the same reasons. This construction also provides an annular space suitable for connection with the inlet pipe 22 for the high pressure air to be separated, although the lower end of the interchanger is warm and inlet pipe 22 is not subject to being clogged with ice. The annular opening between outer head 20 and floating head 19 provides an exit for water which has condensed out of the compressed air as it is cooled in flowing up through the interchanger. This water is drained from outer head 20 through drain pipe 30 to a trap not shown.

Tube 23 projects from floating head 19 through a stuffing box in outer head 20. This stuffing box is formed in outer head 20, and suitable packing is held in the annular space shown around tube 23 by means of gland 24 and bolts 25.

In order to keep the returning oxygen separate from the returning nitrogen, the portion of tubes 1 containing oxygen are embraced within

tube 26 which is soldered or brazed into a groove 27 in tube sheet 4. Tube 26 is of a diameter suitable for the flow of oxygen involved and is enlarged at the upper end to fit into groove 27. 5 Tube 26 projects through tube 23 to a flange 28 for connecting with outside oxygen piping. The annular space between tubes 23 and 26 serves for returning nitrogen which may be recovered if desired through pipe 29. Or, this annular space 10 can be left open to the atmosphere for discarding the nitrogen by simply providing braces for internal pipe 26 to support the same. A solidly brazed or welded construction is shown in the drawing for pipes 23, 26, etc. A flanged and 15 bolted construction could be used as described and shown at the upper end of the interchanger for the returning oxygen and nitrogen tubes, but this will usually be unnecessary at the warm end of the interchanger. 20 In the operation of the interchanger shown in the drawing, very high pressure compressed air enters pipe 22 at about room temperature and flows up in the space within shell 2 surrounding tubes 1. The compressed air may be caused to 25 flow back and forth across the tubes by baffles 31. The compressed air finally leaves through pipe 7 cooled to a very low temperature.

Returning oxygen and nitrogen at very low 30 temperatures enter pipes 17 and 18 and flow down through tubes 1 in heat interchange with the compressed air flowing up and across these tubes. The returning oxygen and nitrogen are thereby warmed nearly to room temperature before leaving through pipes 28 and 29, respectively.

35 During the cooling of the compressed air, water vapor will be frozen out of the compressed air and will accumulate as snow and ice around tubes 1. When this occurs to an extent which appreciably increases the pressure drop or decreases the heat transfer, the oxygen and nitrogen may be returned through another interchanger. The warm air entering pipe 22 will 40 then melt the snow and ice and will warm tubes 1 and shell 2. The resulting water may be 45 drained out through drain pipe 30.

Any relative expansion of tubes 1 and shell 2 will cause floating head 19 to move relative to outer head 20. Such movement can take place without setting up undue strains by reason of the stuffing box with suitable packing material permitting pipe 23 to slide through outer head 20 without leakage of high pressure air.

By use of an extension of the same type of construction described herein, three separate fluids have been caused to flow through three groups 55 of tubes in heat interchange with a single fluid surrounding the tubes. The same type of construction can thus be extended to any number of fluids.

60 In operation, this interchanger is not subjected to high temperatures which would anneal any of the metals used therein. Cold worked metal can therefore be used with high working stresses which are safe for metal in such con-

dition. During construction, however, certain parts become annealed by reason of high temperatures experienced in soldering, brazing or welding to secure the fused metal joints necessary in gas processing, particularly under high 5 pressure. The construction claimed in this patent application enables such annealed parts to be reinforced, thus permitting full advantage to be taken of the high working stresses permissible in non-annealed parts. This is of particular 10 advantage with high gas pressures.

While these improvements have been made particularly for use with high gas pressures they are also of advantage with moderate pressures.

What I claim is:

1. An interchanger for heat exchange between two fluids flowing through tubes and a third fluid surrounding said tubes, including a tube sheet into which said tubes are affixed, a shell fastened to said tube sheet so as to embrace a 20 portion of said tubes, a flange attached to said shell, a cap, a flange attached to said cap, a pipe connection to said cap, a second shell clamped between said flanges and fastened to said tube sheet so as to embrace said tubes, a pipe connection to said second shell, whereby two fluids 25 flowing through the two pipe connections respectively flow through the portion of said tubes embraced by the first shell and the remaining tubes 30 embraced between the two shells and are brought into heat exchange with a third fluid surrounding said tubes.

2. An interchanger for heat exchange between two fluids flowing through tubes and a third fluid 35 surrounding said tubes, including a tube sheet into which said tubes are affixed, a floating head affixed to said tube sheet, an outer head surrounding said floating head, a tube connected to said floating head and projecting through said outer head, an inner tube projecting through said 40 tube and fastened to said tube sheet so as to embrace a portion of said tubes, and a stuffing box in said outer head and surrounding said tube and filled with packing material, whereby two fluids 45 flowing through said inner tube and the annular space between the two tubes respectively flow through the portion of said tubes embraced by said inner tube and the remaining tubes and whereby said floating head may move relative to said outer head without leakage of a third fluid 50 surrounding said tubes and said floating head.

3. An interchanger for heat exchange between fluids flowing through tubes and another fluid surrounding said tubes, including a multiple compartment head having an inner compartment 55 partially bounded by a flanged shell, a cap with a flange attached thereto, and an outer compartment partially bounded by a shell clamped between said flanges, whereby leakage of fluid from the inner compartment into the outer compartment or into the atmosphere is prevented.

WILLIAM LANE DE BAUFRE.
